United States Patent Office.

WALTER D. WOODS, OF BENNINGTON, NEW HAMPSHIRE, ASSIGNOR TO
HIMSELF AND EBENEZER F. WOODS, OF SAME PLACE.

Letters Patent No. 82,779, dated October 6, 1868.

IMPROVEMENT IN CUTLERY.

The Schedule referred to in these Letters Patent and making part of the same.

TO ALL PERSONS TO WHOM THESE PRESENTS MAY COME:

Be it known that I, WALTER D. WOODS, of Bennington, in the county of Hillsboro, and State of New Hampshire, have invented a new and useful Improvement in Table-Cutlery; and do hereby declare the same to be fully described in the following specification, and represented in the accompanying drawings, of which—

Figure 1 is a side view,

Figures 2 and 3 are longitudinal sections, and

Figures 4 and 5 are transverse sections of a fork, having its handle, shank, and bolsters formed and applied together in accordance with my invention.

The planes of section of figs. 2 and 3 are to be supposed to be at right angles, and through the axis of the handle. Those of figs. 4 and 5 are transverse to the said axis, fig. 4 being at the dotted line *a b*, and fig. 5 being at the dotted line *c d* of fig. 1.

In carrying out my invention, I connect the tang of the article of cutlery, whether such article be a knife or a fork, to the handle, and at the same time form the bolster, as well as other parts, by means of casting metal into and on the handle and tang while both are in a matrix or mould.

In the specification of Letters Patent, No. 63,598, I described a mode of connecting the handle and tang of an article of cutlery, by metal cast on the two when laid in a matrix, the bolster being formed by such metal, which at the same time was cast along both the outer edges and around the end of the handle, and constituted what is termed an "encompassing lining."

In my present invention this lining is dispensed with, and the handle is formed tubular, or with a bore or passage extending through it axially, in order that the metal while being cast in the mould may flow entirely through and fill such bore or passage, and form and connect bolsters at both ends of the handle.

I also form within such handle, and for reception of the tang of the blade or fork, a chamber, having a transverse section greater in area than that of the tang, the same being so as to enable the metal to flow entirely around the tang, and form a socket for supporting it on all sides.

Furthermore, I form transversely through the handle, and from the bore thereof, one or more passages, which may be cylindrical, or, what is better, may be conical in opposite directions, the purpose of each of such passages being to form the metal, which while being cast will enter and fill them, substitutes for rivets going through the handle, to prevent it from cracking or splitting, or, in other words, to strengthen it.

In the drawings—

A denotes a fork, of which *o* represents the tang, the whole being stamped or formed of sheet metal. *B* is the handle, which may be of wood, ivory, bone, or other suitable material.

This handle is exhibited in longitudinal sections in Figures 6 and 7, and in transverse sections in Figures 8 and 9.

The bore of the handle is shown at *f*, the tang-socket chamber being represented at *g*, and the rivet-forming passage being seen at *h*.

Furthermore, each end of the handle, I usually bevel in manner as shown at *i i*.

The tang has a hole, *k*, through it when it is to be covered by the front bolster, *C*. Such tang also has another hole, *l*, made through it, in line with the rivet-passage of the handle.

The purpose of these holes is to enable the metal to pass through and fill them, and thereby aid in securing the tang in place.

D denotes the rear bolster; *E*, the connection formed by the metal cast in the bore of the handle; *m* and *n* represent the metal cast through the holes in the tang *o o*. The metal cast into the rivet-holes of the handle *p* is the metal cast in the chamber *g* to form the socket for supporting the tang. All the metal cast into the handle and against its ends, when set, is in one piece.

After being so cast, it will be seen only at the ends of the handle, and at what may be termed rivet-holes,

whereas, in my mode of connecting the handle and the tang, as described in the aforesaid patent, the metal is shown as lining the handle on its opposite edges.

I do not herein claim to connect a knife or fork-handle to the tang of its blade by metal cast on the two.

I herein make no claim to any invention described in Letters Patent, No. 27,790, dated April 10, 1860. My invention differs therefrom in having a passage extending entirely through the handle, and with the metal cast through such passage, and also in the ends of the handle, so as to form bolsters.

Furthermore, I am aware of the subject of the patent, No. 57,521, dated August 28, 1866. My invention differs from that in various particulars: First, the metal for forming and connecting the bolsters is not cast or founded in a handle, but has simple plates of wood, ivory, or other substances riveted on its opposite sides, the metal extending through or to the opposite edges of the handle, but in my handle the metal is cast therein on the tang, and so as to go entirely through the handle, and form bolsters at its opposite ends, without going through or to the opposite edges of the handle.

What I do claim as my present invention or improvements, is as follows:

I claim the handle B, made tubular throughout its length, and having the connection-piece E of the two bolsters arranged in the bore of such handle, as specified.

I also claim the handle as made with the tang-socket chamber g, arranged in it in manner, and to open out of its upper end, and with a passage, f, extended from such chamber to the rear of the handle, as set forth.

I also claim, in combination with the chamber or socket-mould g, formed in the handle, as set forth, the metallic bolster C and tang-supporter p, cast in one piece in and against the handle, and on the tang, as set forth.

I also claim the combination of the rivet-projection passage h of the handle B with the bore f g thereof, as set forth.

And in combination with the handle B and its metallic bolsters C D and their connection E, when cast in one piece in the handle, as described, I claim the rivet-projecting moulding-passage of the handle, and the metal o cast therein, and in one piece with the connection E, as specified.

I also claim the combination of the rear tang-hole l with the metallic extension n, the rivet-projection o, and its moulding passage h of the handle B, as set forth.

I also claim the handle as formed tubular throughout, or from end to end, and with the two bolsters and their metallic connection cast in one piece with respect to such handle, and upon the tang of the blade, the whole being substantially as described.

W. D. WOODS.
